UNITED STATES PATENT OFFICE.

SAMUEL W. AVIS, OF HARTFORD, CONNECTICUT, ASSIGNOR TO THE MERROW MACHINE COMPANY, OF HARTFORD, CONNECTICUT, A CORPORATION OF CONNECTICUT.

OVERSEAMING-MACHINE.

1,319,262.

Specification of Letters Patent.

Patented Oct. 21, 1919.

Application filed October 19, 1915. Serial No. 56,714.

To all whom it may concern:

Be it known that I, SAMUEL WALTER AVIS, a citizen of the United States, residing at Hartford, in the county of Hartford,

5 State of Connecticut, have invented certain new and useful Improvements in Overseaming-Machines; and I do hereby declare the following to be a full, clear, and exact description of the same, reference being had 10 to the accompanying drawings, forming a part of this specification, and to the figures and letters of reference thereon.

This invention relates to sewing machine guides of that type employed to facilitate 15 the application of a strip upon fabrics to which the strip is to be secured by stitching.

The term "strip" is here used in a generic sense to include ribbon, cord, tape or other similar material.

20 It is frequently desirable, as in finishing the edges of underwear, to include such a strip along certain portions of over stitching and exclude it along other portions. To do this a shiftable guide may be employed 25 to advantage and the provision of such a guide, comprised of few parts, compact in form, and simple in operation, is the primary object of the present invention. Other 30 objects of the invention will hereinafter appear.

In the drawings accompanying and forming a part of the present specification I have shown in detail one form of embodiment of my invention, adapted for use in 35 connection with a Merrow overedge sewing machine. It will be understood, however, that the invention is not limited to the exact construction herein shown and described. Its scope is defined by the appended claims.

40 In the drawings,—

Figure 1 is a front elevation of a part of the frame of a Merrow overedge sewing machine, showing the stitch forming mechanism, and in close proximity thereto, my improved guide supported upon said frame.

45 Fig. 2 is an end elevation of the machine shown in Fig. 1 with a cover removed to disclose mechanism beneath the work plate.

Fig. 3 is a sectional view on line 3—3 of 50 Fig. 2.

Figs. 4 and 5 are views in isometrical projection showing a movable part of the guiding device in different positions and its relation to stitch forming elements.

55 Figs. 6 and 7 are sectional detail views

showing the guide mechanism support detached from the machine frame and indicating respectively different positions of the movable parts.

Fig. 8 is a detail view of the guide mechanism and its support as it would appear from that side which is, when the support is in place, contiguous to the machine frame, and

Fig. 9 is an enlarged detail view showing the guide proper in longitudinal section and certain other parts associated with said guide.

Like characters of reference designate similar parts throughout the several views of the drawings.

The stitch forming elements in the over-edge sewing machine illustrated comprise the usual eye pointed needle 1, crochet hook 2, supplemental thread carrier 3 and chaining finger 4. The needle 1 is secured in the bar 5, which is reciprocable in bearings 6 and 7 of the upper part or head 8 of the machine frame 9. Means for reciprocating and oscillating the crochet hook 2 include a pair of cam cylinders 10 and 11 secured respectively to the driving shaft 12 and the shaft 13. Gears 14 and 15 connect the two cam cylinders 10 and 11 so that shaft 12 will, when rotated drive the cam cylinders 13 and shaft 13 in unison therewith. In the machine frame opposite the cam cylinders a frame cap 16 is removably fitted, having on its inner face a guideway 17 to receive a slide 18. Pivoted to said slide is a carrier 19 provided with an arm 20, and with oppositely disposed arms 21 and 22. In the arm 20 is secured the shank of crochet hook 2, arm 21 is provided with a stud 23 and roll 24, and arm 22 is provided with a stud 25 and roll 26. These roll-bearing studs extend respectively into grooves 27 and 28 in the respective cam cylinders 10 and 11. By virtue of the connections just described the crochet hook will, upon rotation of the cam cylinders, be actuated to coöperate with the needle and supplemental thread carrier in a manner well known in this art to produce crocheted overedge stitches.

The stitches thus made may be spaced uniformly upon the edge of the fabric, producing the plain crochet finish, or the stitches may be made in connected clusters thus producing the shell stitch finish, the difference being in the feeding of the fabric

which in the one case is preformed for each cycle of overedge stitching operations and in the other case once for each several cycles of stitching operations.

5 It will be understood, however, that the present invention is not limited in its use to the particular kind of stitching or feeding shown but is intended for general use, though more especially for use in connection with some sort of overedge stitching.

Referring to Fig. 2 the feed mechanism of the machine illustrated will now be briefly described. The feed dog 30 is mounted for sliding movement in an arm 31 pivoted at 15 32. Projecting through a slot 33 in arm 31 is a stud 34 adapted to be engaged by the forked end 35 of the lever 36 which is pivoted at its other end on shaft 37, the latter being secured in the machine frame. Ad- 20 justably secured to lever 36 is one end of a link 38 which at its opposite end engages an eccentric 39 on driving shaft 12. Each rotation of said shaft 12 will effect one stitch forming cycle of the stitch forming 25 elements, and the feed dog, through the eccentric 39, link 38 and lever 36 will be moved through a complete stroke forward and back. This stroke however, will be ineffective for feeding the fabric unless the 30 teeth of the feed dog are raised above the work plate 40 during the movement of said feed dog in the direction of feed. If then, this raising of the feed dog is effected intermittently at intervals of several stitch 35 forming cycles, it follows that the needle will penetrate the fabric repeatedly at or near one point thereby securing as many stitches at each point as there are stitch forming cycles during the intervals when 40 the feed dog remains below the work plate.

As shown, cam means are employed for raising the feed dog into operative position. The feed dog supporting arm 31 is provided with an adjustable shoe 43 having an inclined face 44 which rests on a roller 45 carried on a stud 46 at the end of a lever 47. The latter is mounted on a pivot 48 upon which it may be swung by a cam 49 secured to, and rotatable with a gear 50 which meshes with a pinion 51. Said gear 50 is mounted on a stud 52 and the pinion 51 is secured to the driving shaft 12.

To properly hold the work and to co- 55 operate with the feed dog in effecting the feed the usual presser foot 55 is provided. The width of said presser foot may be increased to cover the extension 30' of feed dog 30 by securing to one side thereof by screw 56, (see Fig. 3) a laterally extending 60 piece 57 having a depending ear 58 which serves as a rear guide for the work. The work may be located and guided in front of the presser foot by a guide 59, which, as usual, is adjustably secured to the machine 65 frame.

Certain thread guides, tensions, etc., appearing in the drawings need not be herein described in detail.

The foregoing is descriptive of simply one style of sewing machine with which my 70 improved guiding device may be employed. The guiding device itself which forms the subject of the present invention will now be described.

Secured to the end of the machine frame 75 adjacent to the stitch forming elements is a support 60 recessed as at 61 to form a housing to receive movable parts of the guide positioning mechanism. The guide proper comprises a tube as 63 which is shown as 80 flattened, this form being particularly adapted for guiding tape or ribbon into the edge finish in a flat condition. Pivotally mounted within the recess 61 of the support 60 on a stud 64 is a carrier 65 for tube 63. 85 Carrier 65 is slotted to receive the reduced end of a latch 66, said reduced end designated by 67 being pivoted to the carrier by a stud 68. Extending beyond the support 60, latch 66 terminates at its outer end 90 in a hooked finger grip 69, while about midway of its length said latch is provided with separated notches 70 and 71 either of which may engage a latch pin 72. When notch 70 engages pin 72 (see Figs. 4 and 95 6) the carrier and its tubular guide will be positioned to lead the strip 75 without the field of stitch formation. In order to position the carrier and guide to lead said strip within the field of stitch formation the 100 latch is moved so that notch 71 engages pin 72, (see Figs. 5 and 7). When in this last mentioned position it will be noted that the delivery end of the flattened guide tube 63, with respect to its width is somewhat 105 oblique to the plane occupied by the strip 75, when the latter is finally covered by stitching. The resulting cross-wise inclination of the strip as it emerges from the guide tube corresponds generally to the inclination 110 of the crochet hook as it passes over the chaining finger above the strip. That is, the strip presents merely its thickness in a plane substantially parallel with that of the path of the crochet hook thereabove and 115 therefore maximum clearance is afforded between said crochet hook and strip.

Bearing against the back of latch 66 about opposite the pin 72 is a spring 76 held in a groove in support 60 by a clamp block 77 120 which is secured by a screw 78, the purpose of said spring being to hold the latch and parts associated therewith in either of the positions to which they may be adjusted. Manipulation of the finger grip 69 to shift 125 the guide and its carrier from the position in which they are shown in Figs. 4 and 6 to the position in which they are shown in Figs. 5 and 7 involves simply raising the latch 66 against the pressure of spring 76 130

until notch 70 disengages pin 72 and then pushing said latch inward until the shoulder 71 engages pin 72, from which position the latch when released will be moved by 5 spring 76 to engage notch 71 over pin 72. A similar manipulation of latch 66 to that just described, with an intervening pull on the finger grasp to engage shoulder 70 against pin 72 will shift the guide and its 10 carrier from the position in which they are shown in Figs. 5 and 7 to the position in which they are shown in Figs. 4 and 6. This construction of the guiding device which permits of the extreme simplicity of 15 operation set forth, embodies an arrangement, which confines all of the movements of the parts to a single plane, thus reducing to a minimum the attention required in its use. Furthermore the transverse extent 20 of the parts comprising the guiding device, with respect to the single plane in which their movements take place, is comparatively very slight, so that a view desirable to one operating the machine is not obscured, and 25 in no way does the construction interfere with convenient accessibility to adjacent parts of the machine.

It is quite desirable that a slight tension 30 be placed upon the strip 75 as it is directed by its guide for inclusion with the stitches of an edge finish and furthermore that such tension be released when the guide is positioned to exclude the strip from the edge finish. This may be accomplished in any 35 convenient manner but I prefer to use a spring as 79 to effect the desired result, said spring being secured by a screw 80 in a channeled block 81, the latter being suitably mounted on the tube 63. Near its free end 40 said spring is bent to form a contact portion 82 adapted normally to extend into an opening 83 in tube 63 and bear slightly against the strip therein. When the 45 guide is shifted to exclude the strip from the stitching the extended free end 84 of spring 79 engages a stop-finger 85 by which said spring is lifted to carry the contact portion 82 away from the strip. The stop-finger 85 may be mounted and held by a 50 screw 87 which also serves to adjustably secure to the machine frame the guide 59 above mentioned.

Having thus described my invention what I claim is,—

55 1. In combination with stitch forming mechanism, a support, a carrier fulcrumed in said support, a strip guide at one end of the carrier, a tension device mounted on the strip guide, a latch for adjusting the 60 carrier, and means for engaging the tension when the carrier is in one of its positions whereby the tension device will be moved from its normal position.

2. In combination with stitch forming 65 mechanism, a support having separated side

walls, a carrier fulcrumed on a pivot extending between said side walls, a strip guide at one end of said carrier, a latch pivoted at the other end of the carrier, means engageable by the latch for holding 70 the carrier in different positions, and means for normally holding the latch in engagement with said latch engageable means.

3. In a sewing machine, in combination with stitch forming elements, a work plate, 75 a strip guide carrier support recessed to form a housing and mounted in fixed position on the machine frame above the work plate, a strip guide, a carrier for the strip guide movably mounted in the support to 80 move in parallelism to a plane extending in the direction of the feed and coinciding with the path of the needle to thereby change the proximity of the strip guide to the work plate, an actuating latch associated 85 with the carrier within the housing, and means for engaging the latch to hold it in different positions.

4. In combination with stitch forming mechanism, a work plate, a feed dog having a laterally extended feeding portion, a presser foot covering the laterally extended portion of the feed dog and having a depending guide flange, a strip guide supported so that one edge of the delivery end 95 thereof will be in constant substantial alignment with the depending guide flange of the presser foot, and means for moving said strip guide whereby a strip carried by the guide may be directed within or without the field of stitch formation. 100

5. In a sewing machine, in combination with stitch forming elements, a work plate, a strip guide carrier support mounted in fixed position on the machine frame above 105 the work plate, a carrier fulcrumed in the support, a strip guide on the carrier, and a latch pivoted to the carrier, the carrier fulcrum and latch pivot being in substantial parallelism with each other and with the 110 work engaging surface of the work plate, whereby the strip guide may be swung vertically toward and from the work plate.

6. In a sewing machine, in combination, 115 a work plate, stitch forming elements including a crotchet hook operable in a path extending over the work plate in a plane oblique thereto, a flattened strip guide having the major transverse axis of its delivery end substantially in parallelism with 120 that part of the crotchet hook path which overlies the work plate, and means above the work plate for movably supporting the strip guide, whereby the strip guide may be actuated to move its delivery end in front 125 of and below the crotchet hook path or above and behind the crotchet hook path.

7. In a sewing machine, in combination, 130 a work plate, a needle operable in a path extending above and below the work plate,

an implement movable in a path extending over the work plate in a plane oblique thereto to coöperate with the needle, a flattened strip guide having the major transverse axis of its delivery end substantially in parallelism with that part of the implement path which overlies the work plate, a tension device associated with the strip guide, means for movably supporting the strip guide whereby the latter may be actuated to move its delivery end above and below the implement path respectively on opposite sides thereof, and means for engaging the tension device to render it ineffective.

8. In a sewing machine, in combination with stitch forming elements, a work plate, a strip guide carrier support mounted in fixed position on the machine frame above the work plate, a strip guide, a carrier for the strip guide movably mounted in the support to move in parallelism to a plane extending in the direction of the feed and co-

inciding with the path of the needle to thereby change the proximity of the strip guide to the work plate, and a carrier actuating latch movable in parallelism to the plane of movement of the carrier.

9. In a sewing machine, in combination, a work plate, stitch forming elements including an implement operable in a path extending over the work plate in a plane oblique thereto, a flattened strip guide having the major transverse axis of its delivery end substantially in parallelism with that part of the implement path which overlies the work plate, and means for movably supporting the strip guide whereby it may be actuated to move its delivery end above and below the implement path respectively on opposite sides thereof.

SAMUEL W. AVIS.
